UNITED STATES PATENT OFFICE

MAJOR TAYLOR CLARK, OF ELMFSORD, NEW YORK

CIRCULAR GRIP PLIERS

Application filed September 28, 1932. Serial No. 635,253.

This invention relates to pliers which are mainly designed for removing bulbs from electric light sockets but which of course can be used for other purposes, the general object of the invention being to provide the pliers with jaws of substantially semi-circular shape in cross section and having teeth on their inner surfaces for gripping the base of the bulb so that the bulb can be removed easily and quickly and without danger of breaking the bulb, which often results in injury to the operator's hands.

This invention also consists in certain other features of construction and in the combination and arrangement of the several parts to be hereinafter fully described, illustrated in the accompanying drawing and specifically pointed out in the appended claim.

In describing the invention in detail reference will be had to the accompanying drawing wherein like characters denote like or corresponding parts throughout the several views, and in which:—

Figure 1 is an elevation of the improved pliers.

Fig. 2 is a section on line 2—2 of Fig. 1.

Fig. 3 is an end view of one of the jaws showing how it is attached to a part of the pliers.

Fig. 4 is a sectional view showing how the pliers are used to remove an electric light bulb.

As shown in these views, the pliers comprises a pair of members 1 and 2 which are pivotally connected together intermediate their ends as shown at 3 with a spring 4 having a part coiled around the pivot with its ends engaging the handle parts of the members 1 and 2 for normally holding the jaw carrying parts separated, as shown in Fig. 1.

As shown in these figures, the members 1 and 2 are preferably of channel-shape in cross section. Each jaw carrying part of the members 1 and 2 is of slightly curved construction as shown in Fig. 1 with its end provided with a curved part 5 on its inner face which forms a seat for the semi-circular jaw 6, said jaw being fastened to the seat

forming part by the rivets 7, or otherwise, as shown in Fig. 3.

Each jaw has teeth 8 on its inner surface and when the pliers are closed the jaws form a substantially circular gripping part 5 for engaging an object such as the base of a bulb B in Fig. 4 whereby the bulb can be easily removed from the socket A in Fig. 4 without danger of breaking the bulb or damaging the parts of the socket. Each jaw 6 is exteriorly flared or tapered as shown at 9 so that the jaws can readily grip a part of the base of the bulb by entering the flaring part of the porcelain portion of the socket, as shown in Fig. 4.

As shown in Fig. 2, the jaws extend lengthwise at right angles from the members 1 and 2 of the pliers and the teeth carrying part of each jaw is thickened so that the thin portion will not contact the bulb as shown in Fig. 4.

Thus it will be seen that I have provided simple means including semi-circular jaw members for removing bulbs from their sockets without danger of breaking the bulbs or injuring the parts of the sockets.

It is thought from the foregoing description that the advantages and novel features of the invention will be readily apparent.

It is to be understood that changes may be made in the construction and in the combination of and arrangement of the several parts provided that such changes fall within the scope of the appended claim.

Having thus described my invention, what I claim as new is:—

A device of the class described comprising a pair of members pivotally connected together intermediate their ends and each including a handle part and a jaw carrying part, the free end portion of each jaw carrying part having its inner face of concave shape, a pair of substantially semi-circular jaws of considerable length and extending at right angles to said jaw carrying parts, each jaw having a part of its convex face fastened in the concavity of a jaw carrying part, with one end of a jaw flush with one face of the jaw carrying part and the other end projecting beyond the other face of said

jaw carrying part, said projecting portion of the jaw being exteriorly tapered and said jaw having a thickened portion extending from the outer end of the projecting portion 5 to a point an appreciable distance from that end of the jaw which is flush with one face of the jaw carrying part, said thickened portion being located on the inner face of the jaw and longitudinally extending 10 teeth on said thickened portion.

In testimony whereof I affix my signature.
MAJOR TAYLOR CLARK.
